UNITED STATES PATENT OFFICE.

JAY S. MEYER, OF PHILADELPHIA, PENNSYLVANIA.

REFRIGERATOR.

Application filed July 28, 1922. Serial No. 578,190.

To all whom it may concern:

Be it known that I, JAY S. MEYER, a citizen of the United States, residing at Philadelphia, in the county of Philadelphia and State of Pennsylvania, have invented certain new and useful Improvements in Refrigerators, of which the following is a specification.

My invention relates to refrigerators and the object of the invention is to provide a refrigerator which, though useful for general refrigeration purposes is especially adapted for use in displaying and dispensing goods, such as chocolate covered confections, which are injuriously affected by heat.

In the drawings:

Figure 1 is a perspective view of a refrigerator embodying my invention,

Figure 2 a vertical cross section of the same,

Figure 3 a fragmentary section at right angles to that shown in Figure 2, and

Figure 4 a perspective view of a tray which is an element of the invention.

The invention may be briefly described as consisting of a casing with closed bottom and back, front and sides consisting of double walls of glass, an ice container, drip tray and removable trays designed to support the goods to be dispensed.

Referring to the drawings, the numeral 1 indicates the base, 2 the back, 3 corner posts at the front, 4 bars or rails at the top connecting the back with the posts and the posts with each other, 5 and 5^a double walls of glass, or other translucent non-heat conducting material, spaced apart to provide a dead air space, 6 an ice container, shown as detachably suspended from screws 7 in the rear wall, 8 a hinged lid or cover for the ice container, 9 a drip tray, shown in the form of a drawer arranged to slide in a rectangular opening in the rear wall just above the base and between guide bars 10, 11 a tray adapted to support the goods to be dispensed, and slideable vertically in the front of the casing between the translucent wall and the ice container. In the form shown the tray comprises a shelf 12, end walls 13,

50 a top 14 and a reenforcing rod 15 connecting the shelf and top. I also provide trays 16 adapted to serve the same purpose as tray 11 but slideable in the sides of the casing. In the form shown these trays consist of a shelf 17, a top 18 and two bars or rods 19 connecting the shelf and top. The top 14 is of

larger dimensions than shelf 12 and, when in position, overlaps the front rail 4, the front edge of lid 8 and side rails 4. Tops 18 extend beyond shelves 17 in three directions and, when in position, overlap one end of lid 8, one side rail 4 and back 2. Lid 8 and tops 14 and 18 thus provide a closed cover for the casing.

The ice container is preferably provided with a ring 20 for convenience in lifting it out of the casing and the drip tray and display trays are provided with suitable knobs or hand holds.

Either tray, with its contents may be easily removed without uncovering the ice container or disturbing the other trays.

Obviously the panels of glass should be so set that their edges will be hermetically sealed to provide an air tight dead air space.

While I have described my invention as taking a particular form it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

1. A refrigerator consisting of a casing having side and front walls of double translucent non-heat conducting material, an ice container disposed within the walls of the casing, and an article container extending to the top of said casing between each side wall and the ice container, each container having a top and being removable from said casing without disturbing the top on any other container.

2. A refrigerator consisting of a casing having one or more double walls of translucent non-heat conducting material, an ice container disposed within the walls of the casing, and one or more trays removably disposed between the ice container and the walls the tops of said trays forming part of the top for the casing.

3. A refrigerator consisting of a casing having one or more double walls of translucent non-heat conducting material, an ice container disposed within the walls of the casing, a lid closing the ice container, and one or more trays removably disposed between the ice container and the walls, said

trays having top members which rest on the upper edges of the side walls.

4. A refrigerator consisting of a casing having one or more double walls of translucent non-heat conducting material, an ice container disposed within the walls of the casing, a drip tray disposed under the container and slidably removable from the casing, and one or more trays disposed between the ice container and the walls and being slidably removable through the top end of said casing.

5. A refrigerator consisting of a casing having side and front double walls of translucent non-heat conducting material, an ice container disposed within the casing, and vertical slidable trays removably positioned between the ice container and the front and side walls of the casing.

6. A refrigerator consisting of a casing having side and front double walls of translucent non-heat conducting material, an ice container disposed within the casing, a lid

covering the ice container, trays removably disposed between the ice container and the front and side walls of the casing, the lid and the tops of the trays constituting the cover of the casings.

7. A refrigerator consisting of a casing having side and front double walls of translucent non-heat conducting material, an ice container disposed within the casing, a lid covering the ice container, trays removably positioned between the ice container and the front and side walls of the casing, said trays having top members which rest on the upper edges of the side walls, the lid and the tops of the trays constituting the cover of the casing.

In testimony whereof I have signed my name to this specification in the presence of two subscribing witnesses.

JAY S. MEYER.
